Patented Nov. 4, 1919.

*Inventor,
Ernest S. Johnson, by
G. C. Kennedy
Attorney.*

UNITED STATES PATENT OFFICE.

ERNEST S. JOHNSON, OF WEBSTER CITY, IOWA.

DESIGN FOR A POULTRY-WATERER.

54,094.

Specification for Design.

Patented Nov. 4, 1919.

Application filed May 20, 1919. Serial No. 298,567. Term of patent 3½ years.

To all whom it may concern:

Be it known that I, ERNEST S. JOHNSON, a citizen of the United States of America, and a resident of Webster City, Hamilton county, Iowa, have invented a new, original, and ornamental Design for Poultry-Waterers, of which the following is a specification, reference being had to the accompanying drawing, forming part thereof.

The figure is a perspective view of a poultry waterer, showing my new design.

I claim:

The ornamental design for a poultry waterer, as shown.

Signed at Webster City, Ia., this 6th day of May, 1919.

ERNEST S. JOHNSON.
